UNITED STATES PATENT OFFICE.

LEO HINZ, OF PERTH AMBOY, NEW JERSEY, ASSIGNOR OF ONE-HALF TO FRIEDRICK MARTIN, OF NEW YORK, N. Y.

AEROPLANE.

1,353,957.

Specification of Letters Patent. Patented Sept. 28, 1920.

Application filed September 22, 1919. Serial No. 325,384.

To all whom it may concern:

Be it known that I, LEO HINZ, a citizen of the German Republic, residing at Perth Amboy, New Jersey, have invented new and useful Improvements in Aeroplanes, of which the following is a specification.

This invention relates to aeroplanes and has particular reference to the stream line construction of the body of the aeroplane, 10 the wings, method of attachment of the wings to the body and the rudders. The invention is illustrated in the accompanying drawings in which Figure 1 is a plan view of the device, Fig. 2 is a side elevation, Fig. 3 15 a front elevation, Fig. 4 a side elevation of one of the rudders, Fig. 5 a sectional view taken through Fig. 4 along the lines 5—5 and Fig. 6 is a sectional side view of the connecting stream line web between the body 20 and wing.

In the drawings, 10 and 11 represent a fore and aft set of triplanes respectively, each built up of superposed planes 12, 13 and 14, and 15, 16 and 17 respectively, each 25 plane being longer than the plane therebelow. The triplanes 10 and 11 carry a body portion or car 21, of stream line construction both in cross section and plan view provided with landing gear 22 and 23. On 30 top of the body portion 21 is provided an observation tower 24.

25 indicates the rudder elements stream line in both cross section and plan view pivoted at 26 in the plane of the center of gravity and having means 27 for controlling them from their rear extremity. Such rudders are located at various places in the machine as desired, but for illustration they are shown at 28 and 29 between the lower 35 set of one triplane and at 30, 31 and 32 between the upper set of a triplane. 33 represents the ailerons of the aeroplane and 34 represents the horizontal control rudders.

The aeroplane is propelled by propellers 45 35 carried by power elements 36 which may be located wherever convenient or desirable to act both as pushers and tractors, as shown in the drawings and particularly in Fig. 1.

Where the lower wings of the triplanes, 50 44 and 17 join the body portion 21, there is provided a stream line weblike connection 37 as shown in Fig. 6 to afford less head resistance when flying.

It will be noticed that the supplemental

power elements 36 are located in a plane 55 just beyond the vertical planes containing the ends of the stabilizing plane 20, which is above the center of gravity of the flying machine and also above the horizontal plane of the top planes of the triplane units or 60 sections.

What I claim is:

1. An aeroplane comprising a body of stream-line construction both in cross-section and plan view, steering elements of 65 stream-line construction in cross-section and plan view, and fore and aft propellers with power elements of stream-line construction, the said steering elements being pivoted in the plane of the center of gravity. 70

2. An aeroplane comprising a body of stream-line construction both in cross-section and plan view, steering elements of stream-line construction in cross-section and plan view, fore and aft propellers with 75 power elements of stream-line construction, the said steering elements being pivoted in the plane of the center of gravity, and a stabilizing plane above the center of gravity of the machine. 80

3. An aeroplane comprising a body of stream-line construction both in cross-section and plan view, steering elements of stream-line construction in cross-section and plan view, fore and aft propellers with 85 power elements of stream-line construction, the said steering elements being pivoted in the plane of the center of gravity, a stabilizing plane above the center of gravity of the machine, and the power elements being located in a plane beyond the planes containing 90 the ends of the stabilizing plane.

4. An aeroplane comprising a body of stream-line construction both in cross-section and plan view, sets of triplanes, steering elements of stream-line construction in cross-section and plan view, and fore and aft propellers with power elements of stream-line construction, the said steering elements being pivoted in the plane of the center of 100 gravity. 95

5. An aeroplane comprising a body of stream-line construction both in cross-section and plan view, sets of triplanes, steering elements of stream-line construction in cross-section and plan view, fore and aft propellers with power elements of stream-line construction, the said steering elements 105

being pivoted in the plane of the center of gravity, and a stabilizing plane above the center of gravity of the machine, said power elements being located in a plane beyond the 5 planes containing the ends of said stabilizing plane.

In testimony whereof, I, LEO HINZ, have

signed my name to this specification in the presence of a subscribing witness, this 10th day of Sept. 1919.

LEO HINZ.

Witness:

Wm. T. JONES.
